ABSTRACT OF THE DISCLOSURE

There are produced 4-aza-benzimidazoles of the formula

where R_1 is fluorine, chlorine or bromine, R_2 is hydrogen or 1-6 carbon alkyl, R_3 is hydrogen, alkyl of 1-6 carbon atoms, alkyl of 1-6 carbon atoms having a phenyl substituent or CH_2COX where X is amino, alkylamino having 1-6 carbon atoms, hydroxy or alkoxy of 1-6 carbon atoms, Y is a halogen, hydroxy, mercapto, amino, alkoxy of 1-6 carbon atoms, beta-hydroxyethylamino, phenylalkylamino in which the alkyl has 1-6 carbon atoms, alkylmercapto of 1-6 carbon atoms, alkylamino with 1-6 carbon atoms, phenyl amino, pyridylamino, alkyl with 1-6 carbon atoms, hydroxyalkyl with 1-6 carbon atoms, trifluoromethyl, phenylalkyl having 1-6 carbon atoms in the alkyl or $-SCH_2COX$, and pharmacologically acceptable salts thereof.

The invention is concerned with 4-aza-benzimidazoles of the formula

where R_1 is fluorine, chlorine or bromine (i.e., halogen of atomic weight 9 to 80), R_2 is hydrogen or 1-6 carbon alkyl, R_3 is hydrogen, alkyl of 1-6 carbon atoms, alkyl of 1-6 carbon atoms having a phenyl substituent or CH_2COX where X is amino, alkylamino having 1-6 carbon atoms, hydroxy or alkoxy of 1-6 carbon atoms, Y is a halogen, hydroxy, mercapto, amino, alkoxy of 1-6 carbon atoms, beta-hydroxyethylamino, phenylalkylamino in which the alkyl has 1-6 carbon atoms, alkylmercapto of 1-6 carbon atoms, alkylamino with 1-6 carbon atoms, phenyl amino, pyridylamino, alkyl with 1-6 carbon atoms, hydroxyalkyl with 1-6 carbon atoms, trifluoromethyl, phenylalkyl having 1-6 carbon atoms in the alkyl or $-SCH_2COX$, and pharmacologically acceptable salts thereof.

Examples of such compounds are 2-methyl-4-aza-5-chlorobenzimidazole, 2-butyl-4-aza-5-chlorobenzimidazole, 2-propyl-4-aza-5-chlorobenzimidazole, 2-benzyl-4-aza-5-chlorobenzimidazole, 2-trifluoromethyl-4-aza-5-chlorobenzimidazole, 2-mercaptop-4-aza-5-chlorobenzimidazole, 2-hydroxy-4-aza-5-chlorobenzimidazole, 2-hydroxy-4-aza-5-bromobenzimidazole, 2-hydroxy-4-aza-5-chlorobenzimidazolyl-(1)-acetic acid, 2-methyl-4-aza-5-chlorobenzimidazolyl-(1)-acetic acid, 1-methyl-2-hydroxy-4-aza-5-chlorobenzimidazole, 2-methylmercaptop-4-aza-5-chlorobenzimidazole,

2

- 4-aza-5-chlorobenzimidazolyl-(2)-mercaptoacetic acid, 2-benzylamino-4-aza-5-chlorobenzimidazole, 2-anilino-4-aza-5-chlorobenzimidazole, 2-hydroxyethylamino-4-aza-5-chlorobenzimidazole, 1-benzyl-2-hydroxy-4-aza-5-chlorobenzimidazole, 4-aza-5-fluorobenzimidazole, 2-isopropyl-4-aza-5-chloro-7-sec.-butyl-benzimidazole, 4-aza-5-bromo-7-hexyl-benzimidazole, 4-aza-5-fluoro-7-ethyl-benzimidazole, 1-hexyl-4-aza-5-chlorobenzimidazole, 4-aza-5-chlorobenzimidazolyl-(1)-acetamide, 2-hydroxy-4-aza-5-chlorobenzimidazolyl-(1)-methylacetamide, 4-aza-5-fluorobenzimidazolyl-(1)-hexylacetamide, 2-hydroxy-4-aza-5-chlorobenzimidazolyl-(1)-methylacetate, 4-aza-5-chlorobenzimidazolyl-(1)-hexyl acetate, 2-chloro-4-aza-5-chlorobenzimidazole, 2-fluoro-4-aza-5-chlorobenzimidazole, 2-bromo-4-aza-5-chlorobenzimidazole, 2-iodo-4-aza-5-bromobenzimidazole, 2-methoxy-4-aza-5-chloro-7-propyl-benzimidazole, 2-ethoxy-4-aza-5-chlorobenzimidazole, 2-hexoxy-4-aza-5-chlorobenzimidazole, 2-phenethylamino-4-aza-5-chlorobenzimidazole, 2-hexylmercapto-4-aza-5-chlorobenzimidazole, 2-amino-4-aza-5-bromobenzimidazole, 2-methylamino-4-aza-5-chlorobenzimidazole, 2-t-butylamino-4-aza-5-chlorobenzimidazole, 2-hexylamino-4-aza-5-chloro-7-methylbenzimidazole, 2-ethyl-4-aza-5-chlorobenzimidazole, 2-propyl-4-aza-5-fluoro-7-ethylbenzimidazole, 2-hexyl-4-aza-5-chlorobenzimidazole, 2-pyridylamino-4-aza-5-chlorobenzimidazole, 2-hydroxymethyl-4-aza-5-chlorobenzimidazole, 2-hydroxyethyl-4-aza-5-chlorobenzimidazole, 2-hydroxyhexyl-4-aza-5-chlorobenzimidazole-2-benzyl-4-aza-5-bromobenzimidazole, 4-aza-5-chlorobenzimidazolyl-(2)-mercaptoacetamide, 4-aza-5-chlorobenzimidazolyl-(2)-methyl mercaptoacetamide, 4-aza-5-chlorobenzimidazolyl-(2)-methyl mercaptoacetate, 4-aza-5-chloro-benzimidazolyl-(2)-hexyl mercaptoacetate, 1-ethyl-2-hydroxy-4-aza-5-chlorobenzimidazole, 1-propyl-2-mercaptop-4-aza-5-chlorobenzimidazole.

The compounds of the invention have valuable pharmacological properties. They are especially noted for their good antiphlogistic activity as well as partially also their antiischemic activity. Especially favorable activity is shown for example in compounds where R_1 is chlorine, R_2 is hydrogen and R_3 is either hydrogen or alkyl with 1 to 6 carbon atoms, especially 1 to 3 carbon atoms in the group CH_2COX while Y is either hydroxy, mercapto or alkyl with 1 to 6 carbon atoms especially 1 to 4 carbon atoms or is trifluoromethyl.

Compounds of the invention can be prepared by either

- (a) Reacting a compound having formula I except that R_1 is hydroxy or etherified hydroxy, e.g., alkoxy, or amino (rather than halogen) with a halogenating agent or
(b) Condensing to an imidazole ring a compound having the formula

where R_1 , R_2 and R_3 are as defined in formula I and V is an amino group, a hydroxy group, are etherified hydroxy group, e.g., alkoxy, or a halogen with a compound having the formula Y—CN or a compound having the formula $Y_1Y_2C=Z$ where Y is as defined in formula I, Z is oxygen, sulfur or defined as for Y or Y_1 and Y_2 together can mean sulfur.

Thus examples of compounds within formula II are 2-chloro - 5,6 - diaminopyridine, 2-bromo-5-amino-6-hydroxypyridine, 2-fluoro-5,6-diaminopyridine, 2-chloro-4-methyl-5-methylamino-6-aminopyridine, 2-bromo-5-hexylamino-5-amino - 6 - methoxypyridine, 2-chloro-4-hexyl-5-benzylamino-6-hydroxypyridine, 2-chloro-5-amino-6-chloropyridine, 2-chloro-5-amino-6-bromopyridine, 2-chloro-5-carboxymethylamino-6-aminopyridine.

Representative compounds having the formula Y—CN are cyanogenchloride, cyanogen bromide, hydrogen cyanide, cyanamide, cyanic acid, thiocyanic acid. Representative compounds having the formula $Y_1Y_2C=Z$ are carbon dioxide, carbon disulfide, carbon oxysulfide, urea, thiourea, guanidine, methyl chloroformate, ethyl chloroformates, hexylchloroformate, phenylchloroformate, methyl bromoformate, diethyl carbonate, β,β -dihydroxyethyl urea, sym.dibenzyl urea, dimethyl dithio carbonate, diethyl trithiocarbonate.

The compounds of the present invention whether prepared by process (a) or process (b) or by other process can be converted into their salts, preferably their salts of pharmacologically acceptable acids such as hydrochloric acid, sulfuric acid, phosphoric acid, acetic acid, succinic acid, maleic acid, fumaric acid, citric acid, lactic acid and p-toluenesulfonic acid.

As stated above according to process (a) there can be used a starting material of formula I where in place of the halogen R_1 is an etherified hydroxy group. Such etherified hydroxy groups are preferably alkoxy groups, for example, having 1 to 6 carbon atoms, e.g., methoxy, ethoxy, propoxy, isopropoxy, butoxy and hexoxy or phenoxy. Thus there can be used 2-benzyl-4-aza-5-ethoxybenzimidazole, 2-mercaptop-4-aza-5-hexoxybenzimidazole, 2-trifluoromethyl-4-aza-5-phenoxybenzimidazole.

In carrying out process (a) there is employed for example an elevated temperature, e.g. 50-200° C. with a halogenating agent such as phosphorus oxychloride, phosphorus pentachloride, phosphorus pentabromide, phosphorus oxybromide, thionyl chloride, thionyl bromide, etc., in a given case with the addition of an inert solvent. As inert solvents there can be used aromatic hydrocarbons such as benzene, toluene, etc. Frequently it is convenient to use an excess of the halogenating agent as the solvent.

In the case of process (a) where the R_1 is replaced by an amino group in the starting material the action of the halogenating agent preferably takes place in combination with a diazolization (Sandmeyer reaction or modified Sandmeyer process) in the presence of the corresponding halide ion and/or the corresponding copper (I) salt or the fluoroborate ion. It is likewise possible to isolate the intermediate product of the Sandmeyer reaction and to decompose it thermally.

Process (b) can be carried out with or without solvents in a temperature range of 0.300° C., for example. As solvents there can be used polar compound, for example water, alcohols, e.g., methyl alcohol, ethyl alcohol, isopropyl alcohol and butyl alcohol, dimethyl formamide, dimethyl sulfonate, dioxane, polyphosphoric acid, etc. Likewise there can be used an excess of the component $Y_1Y_2C=Z$ as the solvent in the event this material is a liquid. In a given case there can be added in process (b) basic compounds such as, for example, alkali hydroxides, e.g., sodium hydroxide and potassium hydroxide, alcoholates, e.g., sodium methylate, potassium methylate, sodium ethylate and potassium ethylate. The use of these alkaline materials is particularly desirable when one reaction component is carbon disulfide.

As starting materials having the formula Y—CN there are especially used compounds where Y is a halogen atom, an amino group, a hydroxy group or a mercapto group.

Process (b) can also be carried out in such a manner that an intermediate product in which the amino group in either the 2 or 3 position of the pyridine ring is substituted by the group —CY=Z is isolated. This intermediate compound is then cyclized with the splitting off for example of water, alcohol, ammonia or an amine. This procedure can be carried out for example with or without a solvent at a temperature between 50 and 300° C. In case a solvent is used those mentioned above can be employed. In a given case there can be added the customary condensation reagents, for example polyphosphoric acid.

If V is an etherified hydroxy group it is preferably lower alkoxy, e.g., methoxy to hexoxy, or phenoxy. In compounds of formula I wherein Y means a halogen atom or a hydroxy, mercapto, amino, alkylmercapto, alkoxy or alkylamino group these groups can be substituted for each other or a different one of the above set forth group Y. This reaction can be carried out with or without solvent at a temperature in the range of 50-250° C. for example. As solvents there can be used for example the polar solvent set forth above, e.g., water, alcohols, e.g., methyl alcohol, ethyl alcohol, isopropyl alcohol, butyl alcohol, dimethyl formamide, dimethyl sulfoxide, etc. Frequently it is expedient to add acid binding agents such as, for example, soda lye, potassium hydroxide, tertiary amines, e.g., trimethylamine, triethylamine, pyridine, alkali carbonates, e.g., sodium carbonate and potassium carbonate, etc.

In the event that Y is a hydroxy group, a mercapto group or an amine group this reaction process (b) can be carried out for example by alkylation using the customary alkylation agents such as lower alkyl halides, e.g., methyl chloride, ethyl chloride, hexyl chloride, isopropyl chloride, butyl chloride, methyl bromide, phenylalkyl halides, e.g., benzylchloride and benzyl bromide, halocetic acid, e.g., chloroacetic acid, bromoacetic acid, iodoacetic acid, alkyl haloacetates, e.g., methyl chloroacetate, methyl bromoacetate and ethyl chloroacetate, haloacetamides, e.g., chloroacetamide and bromoacetamide or by means of the corresponding sulfonic acid esters such as dialkyl sulfates, e.g., dimethyl sulfate or diethyl sulfate, dimethyl sulfoxide, aliphatic arylsulfonic acid alkyl esters, e.g., methyl p-toluenesulfonate and ethyl p-toluenesulfonate, arylsulfonic acid phenyl and benzyl esters, e.g., phenyl p-toluenesulfonate, benzyl p-toluenesulfonate and phenyl benzenesulfonate (see, for example, Fieser and Fieser "Reagents for Organic Synthesis," Vol. 1 (1967) pages 1303-4 and Vol. 2 (1969), page 471, John Wiley and Sons, Inc., New York for other suitable alkylating agents).

In the event Y is a halogen or an alkoxy or alkyl group or an amino or alkylamino group process (b) can be carried out by reacting the compound of formula II with a compound supplying the corresponding Y group, e.g., an amine, e.g., propyl amine, or alcohol, e.g., ethyl alcohol, mercaptoderivative or a base, for example, sodium sulfide or potassium sulfide, alkali hydroxide, e.g., sodium hydroxide or potassium hydroxide, lower alkyl mercaptans, e.g., methyl mercaptane, ethyl mercaptan, t-butyl mercaptan, hexyl mercaptan, lower aliphatic alcohols, e.g., methyl alcohol, propyl alcohol, butyl alcohol, isopropyl alcohol, hexyl alcohol, ammonia, lower alkyl amines containing a phenyl or hydroxyl residue, e.g., benzyl amine, phenethylamine, ethanolamine propanolamine, aniline, a pyridylamine, e.g., 2-aminopyridine, mercaptoacetic acid, alkyl mercaptoacetates, e.g., methyl mercaptoacetate, ethyl mercaptoacetate, isoctyl mercaptoacetate, mercaptoacetamide, mercapto alkyl acetamides, e.g., mercapto methyl acetamide or the customary halogenating agents such as those set forth above for example.

Furthermore compounds of formula I in which R_3 is hydrogen can be converted to compounds in which R_3 is

alkyl, in a given case substituted by a phenyl group or the group CH_2COX if this is reacted with the compound of formula I a lower alkyl halide, e.g., methyl chloride, methyl bromide, ethyl chloride, propylchloride or a phenyl substituted lower alkyl halide, e.g., benzyl halides such as benzyl chloride and benzyl bromide, or a lower alkyl haloacetate, e.g., methyl chloroacetate, ethyl chloroacetate, propyl bromoacetate, or a haloacetamide, e.g., chloroacetamide or bromoacetamide, a haloacetic acid, e.g., chloroacetic acid or bromoacetic acid, or a dialkyl sulfate, e.g., dimethyl sulfate or diethyl sulfate or in a given case in regard to the ester group by a phenyl substituted arylsulfonic acid alkyl ester. This reaction is suitably carried out in inert solvents such as dimethylsulfoxide, toluene, dioxane, etc. with or without the addition of acid binding reagents such as alkate carbonates, e.g., sodium carbonate or potassium carbonate, alkali amides, e.g., sodamide, potassium amide, alkali hydrides, e.g., sodium hydride, lithium hydride, etc. at a temperature, for example, within the range of 20 to 150° C.

With compounds that contain the $-\text{COX}$ group, in the case where X is an amino group, an alkylamino group or an alkoxy group these can be saponified to a hydroxy group, or in case X is a hydroxy group or an alkoxy group it can be converted with a corresponding alkanol having 1 to 6 carbon atoms to an alkoxy group or (when X already is alkoxy) to a different alkoxy group, or by reaction with ammonia or an alkyl amine of 1 to 6 carbon atoms the hydroxy or alkoxy group can be amidated.

When a compound of formula I in which R_3 is hydrogen is reacted in the manner set forth above isomeric mixtures can be formed in which the radical R_3 is on the nitrogen atom in the 3-position of the benzimidazole ring. The desired isomer corresponding to formula I in this case is separated off by fractional crystallization or other customary processes, as for example a chromatographic process (column chromatography) or extraction.

Basic compounds of formula I, as for example 2-benzylamino-4-azo-5-chlorobenzimidazole can be converted to salts by known procedures. As anions for these salts there can be used known and therapeutically usable acid radicals, such as those set forth previously for example.

Compounds of formula I of an acid character, as for example 2 - hydroxy-4-aza-5-chlorobenzimidazolyl-(1)-acetic acid can be converted in the customary manner into their alkali, e.g., sodium or potassium, ammonium or substituted ammonium salts. As substituted ammonium salts there may be noted especially salts of tertiary alkyl amines, e.g., trimethylamine, triethylamine, tributylamine and ethyl dipropylamine, lower aminoalcohols, e.g., ethanolamine and propanolamine, as well as bis and tris (hydroxyalkyl) amines (alkyl radicals having 1 to 6 carbon atoms), e.g., diethanolamine, dipropanolamine, dihexanolamine, triethanolamine and tripropanolamine.

Each compound of formula I which contains asymmetrical carbon atoms and as a rule occurs as the racemate can be split into the optically active isomers in known manner, for example by means of an optically active acid. However, it is also possible from the start to employ an optically active or disastereomeric starting material in which case the final product will have a correspondingly optically active form or disastereomer configuration.

In case the symbol R_3 is hydrogen the compounds of formula I within the invention are tautomeric with compound in which the hydrogen is not on the nitrogen atom in the 1 position of the benzimidazole ring but is on the nitrogen atom in the 3 position of the benzimidazole. The compounds of formula I in this case can be present entirely or partially in both possible tautomeric forms. Generally under normal operating and storage conditions they are present in equilibrium.

PRODUCTION OF THE STARTING MATERIAL For Process (a)

2-amino-3-nitro-6-chloropyridine is reacted in a polar

solvent such as a lower alkanol, e.g., methyl alcohol, ethyl alcohol, isopropyl alcohol, propyl alcohol or butyl alcohol with ammonia, alkali alcoholates, e.g., sodium methylate, potassium methylate or sodium ethylate, or alkali, e.g., sodium hydroxide or potassium hydroxide, in a given case with an excess of the basic component or in a given case in the presence of a tertiary amine, e.g., trimethylamine, triethylamine, tributylamine or dimethyl aniline as hydrochloric acid acceptors at a temperature between 0 and 200° C. In the compounds obtained the nitro group is reduced to an amino group by hydrogenation in the presence of Raney-nickel or noble metal hydrogenation catalysts such as palladium or platinum, suitably at a temperature between 20 and 150° C. in a solvent such as an alcohol, e.g., methyl alcohol, ethyl alcohol or butyl alcohol, dioxane, or tetrahydrofuran and the thus obtained compound is converted to the corresponding imidazole derivative by process (b). The following example illustrates this process.

20 To a solution of 10 grams of sodium in 400 ml. of ethanol there were added at room temperature 50 grams of 2-amino-3-nitro-6-chloropyridine in portions. After the end of the addition heating at reflux with stirring for a further 30 minutes. In the cooling off the reaction product crystallized. It was filtered off with suction and washed with much water and alcohol. Yield 35 grams.

The 2-amino-3-nitro-6-ethoxypyridine was then hydrogenated in 500 ml. of dioxane with addition of 10 grams of Raney-nickel and 20 grams of MgSO_4 at 50 atmospheres excess pressure and 40-50° C. The reaction solution was sucked off over a filter bed, and the filtrate treated with 25 ml. of ethyl chloroformate with stirring. After a short time the 2 - amino - 3 - carbethoxyamino-6 - ethoxypyridine crystallized out which was directly further reacted after filtering with suction and washing. The carbethoxy compound was heated in a round bottomed flask at 220-240° C. for 2 hours with occasional stirring whereupon it began to sinter and ethanol to split off. The residue was recrystallized from dimethyl formamide (DMF) after cooling. There were obtained 15 grams of 2 - hydroxy-4-aza-5-ethoxy-benzimidazole M.P. >300° C.

To a solution of 62 grams 2,3,6-triaminopyridine in dioxane 60 grams of ethylchloroformate are added with stirring. The precipitating 2,6-diamino-3-carboethoxyaminopyridine hydrochloride is filtered off and dried. This compound is heated for 2 hours to 200-220° C. The resulting 2-hydroxy-4-aza-5-aminobenzimidazole.HCl can be recrystallized from methanol. Yield 34 grams; M.P. 258-262° C. From the warm aqueous solution the base can be precipitated by addition of dilute NaOH. M.P. >300° C.

PRODUCTION OF STARTING MATERIAL

For Process (b)

55 A 2,6-dihalogen-3-nitropyridine, e.g., 2,6-dichloro-3-nitropyridine or a 2-amino-6-halogen-3-nitropyridine, e.g., 2-amino-6-chloro-3-nitropyridine was reduced to the 3-amino-pyridine derivative in the presence of Raney-nickel or a noble metal hydrogenation catalyst such as palladium or platinum in a polar solvent such as an alcohol, e.g., ethyl alcohol, methyl alcohol or butyl alcohol, dioxane, tetrahydrofuran, etc. at a temperature between 20 and 150° C., in a given case with pressure. 60 For the production of such compounds in which V of formula II is a hydroxy group or an etherified hydroxy group, for example 2,6-dichloro-3-nitropyridine is reacted with an equivalent alcoholate, e.g., sodium ethylate or potassium methylate or alkali phenolate, e.g., sodium phenolate or potassium phenolate, or an equivalent alkali, e.g., sodium hydroxide or potassium hydroxide, in a given case in the presence of a tertiary amine, e.g., trimethylamine, triethyl amine, tributyl amine or dimethyl aniline 65 70 in a polar solvent at a temperature between -50 and

+100° C., preferably between -50 and +10° C. and the nitro group of the compound obtained is reduced to an amino group by hydrogenation in the presence of Raney-nickel or a noble metal catalyst such as palladium or platinum, for example at a temperature between 20 and 150° C. in a solvent such as an alcohol, e.g., methyl alcohol, ethyl alcohol, isopropyl alcohol or butyl alcohol, dioxane or tetrahydrofuran.

In the thus obtained compounds the R_3 radical can be introduced as follows:

The pyridine derivative can be reacted with an aliphatic carboxylic acid halide having 1 to 6 carbon atoms, e.g., an alkanoic acid halide such as formyl chloride, acetyl chloride, propionyl chloride, butyryl chloride, valeroyl chloride, caproyl chloride or acetyl bromide. The acyl halide can have a phenyl radical attached, e.g., phenyl acetyl chloride. In the reaction the amino group in the 3 position is acylated and subsequently the CO group reduced to the CH_3 group with lithium aluminum hydride or reacted with a compound of the formula

(Hal is chloride or bromine);

or the pyridine derivative is reacted with an aliphatic aldehyde with 1 to 6 carbon atoms, e.g., formaldehyde, acetaldehyde, propionaldehyde, butyraldehyde, valeraldehyde, or caproaldehyde, or an aliphatic aldehyde having a phenyl radical attached, e.g., phenylacetaldehyde or an aldehyde of the formula $OHC-COX$, in a polar solvent (for example alcohols, e.g., ethyl alcohol) for example at 0 to 50° C. and the Schiff base obtained catalytically reduced in the presence of Raney-nickel or noble metal catalysts or sodium borohydride. The process is illustrated by the following example:

50 grams of 2-amino-3-nitro-6-chloropyridine in 500 ml. of dioxane after the addition of 20 grams of $MgSO_4$ and 10 grams of Raney-nickel were reduced at 30-40 atmospheres excess pressure and 30-40° C. The hydrogenated solution was filtered and treated with 100 ml. of 6-normal isopropanolic HCl with stirring, whereupon 2,3-diamino-6-chloropyridine, hydrochloride precipitated. It can be recrystallized from ethanol. The compound is very sensitive to air. Yield 40 grams; M.P. >300° C.

To the solution in dioxane of 2,3-diamino-6-chloropyridine produced above (40 grams in 500 ml. of dioxane) there were added dropwise with stirring 30 ml. of ethyl chloroformate. The 2-amino-3-carbethoxyamino-6-chloropyridine hydrochloride soon crystallized out. The compound can be recrystallized from ethanol. Yield 55 grams; M.P. 190-2° C.

50 grams of 2-amino-3-nitro-6-chloropyridine in 450 ml. of ethanol were hydrogenated after the addition of 20 grams of Raney-nickel at 20-40° C. and 50 atmospheres excess pressure, the solution filtrated and 32 ml. of benzaldehyde added. The Schiff's base which crystallized out was filtered off with suction and recrystallized from acetone. Yield 42 grams; M.P. 180-182° C.

28 grams of the Schiff's base were treated in a mixture of 500 ml. of dioxane and 500 ml. of methanol with 20 grams of sodium borohydride in portions. The temperature of the stirred mixture was held at 30-35° C. After 3 hours there were added 150 ml. of 6 normal isopropanolic HCl and evaporated to dryness. The residue was dissolved in methanol, alkalized with aqueous NaOH and the crystallized 2-amino-3-benzylamino-6-chloropyridine filtered off with suction. Yield 28 grams; M.P. 140-142° C.

2-Methoxy-3-nitro-6-chloropyridine

To a solution of 19.3 grams (0.1 mole) of 2,6-dichloro-3-nitro-pyridine in 200 ml. methanol there were added with stirring in portions 13.8 grams (0.1 mole) of powdered potash. An exothermic reaction resulted; the temperature was held at 10 to 15° C. by cooling. The

mixture was stirred for 2 hours. The dissolved material can be directly reduced on the nitro group.

2 - hydroxy - 3 - nitro - 6 - chloropyridine, for example can also be produced by heating 2-amino-3-nitro-6-chloropyridine with nitrous acid.

The compounds of the invention are suited for the production of pharmaceutical compositions and preparations. The pharmaceutical compositions or drugs contain as the active material one or several of the compounds of the invention, in a given case in admixture with other pharmacologically or pharmaceutically effective materials. The production of the medicine can take place with the use of known and customary pharmaceutical carriers and diluents, as well as other customary assistants.

Such carriers and assistants are set forth for example in Ullmann's Encyklopädie der technischen Chemie, Vol. 4 (1953), pages 1 to 39; Journal of Pharmaceutical Sciences, Vol. 52 (1963), pages 918 *et seq.*; Hiv. Czetsch-Lindenwald, Hilfsstoffe für Pharmazie und angrenzende Gebiete; as well as in Pharm. 2nd. Vol. 2 (1961), pages 72 *et seq.*

Examples of such materials include gelatin, sucrose, pectin, starch, tylose, talc, lycopodium, silica, lactose, cellulose derivatives, micropulverized cellulose, stearates, e.g., methylstearate and glyceryl stearate, emulsifiers, vegetable oils, water, pharmaceutically compatible mono- or polyvalent alcohols and polyglycols such as glycerine, mannitol, sorbitol, pentaerythritol, ethyl alcohol, diethylene glycol, triethylene glycol, ethylene glycol, propylene glycol, dipropylene glycol, polyethylene glycol 400, as well as derivatives of such alcohols and polyglycols, dimethyl sulfoxide, esters of saturated and unsaturated fatty acids with mono- or polyvalent alcohols such as glycols, glycerine, diethylene glycol, pentaerythritol, sorbitol, mannitol, etc., e.g., glyceryl stearate, glyceryl palmitate, glyceryl oleate, ethylene glycol stearate; such esters of polyvalent alcohols can in a given case also be etherified, benzyl benzoate, dioxolano, glycerine formyl, glycol furfural, dimethyl acetamide, lactamide, lactates, e.g., ethyl lactate, ethyl carbonate, etc.

Furthermore there can be added preservatives, stabilizers, buffers, taste correctives, antioxidants and complex formers (for example ethylenediaminetetraacetic acid) and the like. In a given case for stabilization of the active molecule a pH in the range of about 6-8 can be established with physiologically compatible acids or buffers.

As antioxidants there can be used for example sodium meta bisulfite and ascorbic acid, as preservatives there can be used for example sorbic acid, p-hydroxybenzoic acid esters, e.g., methyl p-hydroxybenzoate and ethyl p-hydroxybenzoate and similar materials.

The pharmacological and galenical treatment of the compounds of the invention takes place according to the usual standard methods.

The drugs can be used enterally parenterally, orally, perlingually or in the form of sprays.

The addition of other medicinally active materials is also desirable, especially the addition of analgesically and antiphlogistically effective substances.

The compounds of the invention have a good antiphlogistic and antiischemic activity.

The antiphlogistic activity is comparable to that of the known drug salicylamide.

The lowest effective antiphlogistic dosages in animal experiments for example are

20 mg./kg. body weight—orally
10 mg./kg. body weight—sublingually
5 mg./kg. body weight—intravenously

As a general range of dosage for activity (based on animal studies) there can be employed

20-200 mg./kg. body weight—orally
10-100 mg./kg. body weight—sublingually
75 5-20 mg./kg. body weight—intravenously

The compounds of the invention have utility in treating rheumatic fever, chronic-rheumatic arthritis, Morbus Bechterew, spondylosis, arthrosis, discopathy, gout, fibrosis, periarthritis, neuritis, neuralgia, surface thrombo-phlebitis, angina pectoris and coronary blood flow disturbances.

The addition of other medicinally active material is also favorable, especially analgesically and antiphlogistically effective substances.

The pharmaceutical preparations generally contain between 1 and 50 weight percent of the active component of the invention.

The compounds can be delivered in the form of tablets, capsules, pills, dragees, suppositories, gels, cremes, powders, liquids, dusts or aerosols. As liquids there can be used oily or aqueous solutions or suspensions, emulsions, injectable aqueous or oily solutions or suspensions. The preferred forms of use are tablets which contain between 50 and 200 mg. of active material as solutions which contain between 0.5 and 2% of active material.

In individual doses the amount of active component of the invention can be used for example in an amount of 200 mg. dispensed orally or 10 mg. dispensed intravenously in each case calculated as the free base. These doses can be dispensed once or several times a day.

For example there is recommended the use of 1 to 9 tablets containing 200 mw. of active ingredient 3 times daily or intravenously the injection 1 to 3 times a day of a ml. ampoule having 10 mg. of active material.

The acute toxicity of the compounds of the invention in the mouse (expressed by the LD 50 mg./kg. method of Miller and Tainter, Proc. Soc. Exph. Biol. and Med., Vol. 57 (1944), pages 261 *et seq.*) in oral application is at least 500 mg./kg. for example 8000 mg./kg. in some cases.

The drugs can be used in human medicine, in veterinary medicine, e.g., to treat cats, dogs, horses, sheep, cattle, goats and pigs or in agriculture. The drugs can be used alone or in admixture with other pharmacologically active materials.

Unless otherwise indicated, all parts and percentages are by weight.

EXAMPLE 1

2-Methyl-4-aza-5-chlorobenzimidazole

65 grams of 2-amino-3-acetylamino-6-chloropyridine were heated at 180-200° C. for 45 minutes. The compound became solid during the heating. The product was recrystallized from methanol. Yield 35 grams; M.P. 254-256° C.

EXAMPLE 2

2-Benzyl-4-aza-5-chlorobenzimidazole

40 grams of 2,3-diamino-6-chloropyridine and 45 grams of phenylacetic acid were dissolved in 250 ml. of ethyl alcohol and heated for 15 minutes on the water bath. The alcohol was then distilled off and the residue heated at 190-210° C. for 1 hour. Upon cooling the melt crystallized. To purify the compound it was recrystallized three times from ethyl alcohol using carbon for clarification. Yield 16 grams; M.P. 215-217° C.

EXAMPLE 3

2-Trifluoromethyl-4-aza-5-chlorobenzimidazole

5

10

15

20

25

30

35

40

45

50

55

60

65

70

75

50 grams of 2,3-diamino-6-chloropyridine and 40 grams of trifluoro acid were dissolved in 250 ml. of ethyl alcohol and heated on the water bath for 15 minutes. Then the alcohol was distilled off and the residue heated for 1 hour at 190-210° C. Upon cooling the melt crystallized. For purification purposes the compound was recrystallized twice from methanol employing carbon for clarification. Yield 13 grams; M.P. 228-230° C.

EXAMPLE 4

2-Mercapto-4-aza-5-chlorobenzimidazole

25

30

35

40

45

50

55

60

65

70

75

50 grams of 2,3-diamino-6-chloropyridine were dissolved in 500 ml. of ethyl alcohol. The solution was treated with 50 ml. of carbon disulfide and 15 ml. of 40% sodium hydroxide and heated under reflux for 4 hours. The solution was acidified with hydrochloric acid and the alcohol distilled off. The residue was stirred with water. The crystals were sucked off and then washed with water. The crystals were dissolved in warm sodium carbonate solution, clarified with carbon and the solution filtered. The filtrate was acidified with hydrochloric acid whereupon the compound again crystallized out. Yield 35 grams; M.P. 730° C.

EXAMPLE 5

2-Hydroxy-4-aza-5-chlorobenzimidazole

50

55

60

65

70

75

84 grams of 2-amino-3-carbethoxy-amino-4-chloropyridine were heated at 189-200° C. for 1 hour. The product was purified by recrystallization from dimethyl formamide. Yield 40 grams; M.P. >300° C.

EXAMPLE 6

2-Hydroxy-4-aza-5-bromo-7-methyl benzimidazole

50

55

60

65

70

75

15 grams of 2 - amino-3-carbethoxyamino-4-methyl-6-bromopyridine were heated for 20 minutes at 200° C. The product was purified by recrystallization from dimethyl formamide. Yield 7 grams; M.P. 300° C.

11

EXAMPLE 7

2-Hydroxy-4-aza-5-chlorobenzimidazolyl-(1)-acetic acid

34 grams of 2 - hydroxy-4-aza-5-chlorobenzimidazole were dissolved in 400 ml. of dimethyl formamide. There were then added in portions at 20-25° C. 9.6 grams of NaH (55%). The mixture was stirred for 30 minutes at 20° C. Then they were dropped in 26 ml. of ethyl chloroformate, whereupon the temperature increased to 35° C. The mixture was stirred for 3 hours longer at 60-70° C. Then the solution was poured into 3 liters of water, whereupon the product crystallized. It was sucked off and washed with water. The ester thus obtained was heated for 1 hour under reflux with a solution of 21 grams of potassium hydroxide in 200 ml. of water and 600 ml. of ethyl alcohol. Then the solution was acidified with hydrochloric acid and evaporated to dryness. The residue was dissolved in dilute soda solution. The insoluble starting material was filtered off. The filtrate was acidified with hydrochloric acid, whereupon the acid product crystallized. It was recrystallized from water. Yield 7 grams; M.P. 213-215° C.

EXAMPLE 8

2-Methyl-4-aza-5-chlorobenzimidazolyl-(1)-acetic acid

65 grams of 2-methyl-4-aza-5-chlorobenzimidazole were dissolved in 800 ml. of dimethyl formamide. Then there was added in portions at 20-25° C. 19.6 grams of NaH (55%). The mixture was subsequently stirred for 30 minutes. Then there were dropped in 53 ml. of ethyl chloroformate, whereupon the temperature rose to 35° C. The mixture was stirred for an additional 3 hours at 35° C. The solution was cooled and treated with 50 ml. of water and 25 ml. of acetic acid. The solvent was distilled off in a vacuum. The residue was treated with water, whereupon the product crystallized. In this reaction 2 isomers were formed. The desired compound was obtained in pure form by recrystallizing twice from ethyl alcohol. The thus obtained ester was heated under reflux with a solution of 15 grams of potassium hydroxide in 50 ml. of water and 350 ml. of ethyl alcohol for 1 hour. Then the solution was acidified with hydrochloric acid and evaporated to dryness. The residue was stirred with water. The crystals were sucked off and subsequently washed with water. The product was then recrystallized from water. Yield 7 grams; M.P. 240-243° C.

EXAMPLE 9

1-Methyl-2-hydroxy-4-aza-5-chlorobenzimidazole

50 grams of 2 - hydroxy-4-aza-5-chlorobenzimidazole were dissolved in 700 ml. of dimethyl formamide. There were then added in portions 14 grams of NaH (55%) at 20-25° C. The mixture was stirred for 30 minutes at 20° C. There were then dropped in 46 grams of methyl iodide

12

whereupon the temperature rose to 40° C. The reaction mixture was allowed to stand overnight (16 hours) at room temperature. Then there were added 50 ml. of water and 25 ml. of glacial acetic acid. The solvent was distilled off in a vacuum. The residue was treated with water, whereupon it crystallized. The crystals were sucked off and washed with water. Then they were dissolved in chloroform. The insoluble starting material was filtered off and the filtrate evaporated to dryness. There were obtained 37 grams of a mixture of isomers. The desired compound was separated from its isomers by dry column chromatography (column filling silica gel; running agent; 94 vol. percent CHCl_3 and 6 vol. 7% $\text{C}_2\text{H}_5\text{OH}$). There were obtained 14 grams of product which was recrystallized from ethyl alcohol. Yield 10 grams; M.P. 180-182° C.

EXAMPLE 10

2-Methylmercapto-4-aza-5-chlorobenzimidazole

23 grams of 2 - mercapto-4-aza-5-chlorobenzimidazole were dissolved in 200 ml. of 2.5% soda lye. There were 30 then dropped in 13 ml. of dimethyl sulfate at 30-33° C. The reaction product crystallized out during the reaction. It was filtered off, washed with water and recrystallized from ethyl alcohol. Yield 14 grams; M.P. 233-235° C.

EXAMPLE 11

4-Aza-5-chlorobenzimidazolyl-(2)-mercaptoacetic acid

30 grams of 2-mercaptop-4-aza-5-chlorobenzimidazole were heated with 14 grams of chloroacetic acid and 12 grams of sodium hydroxide in 300 ml. of water for 3 hours at 70° C. The reaction mixture was allowed to stand overnight at room temperature. The solution was filtered and the filtrate acidified with acetic acid. Thereupon the product crystallized out. It was dissolved in dilute sodium bicarbonate solution. The solution was clarified with carbon and filtered. The filtrate was acidified with glacial acetic acid, whereupon the product again crystallized out. It was sucked off and post washed with water. Yield 7 grams; M.P. 218-220° C.

EXAMPLE 12

2-Benzylamino-4-aza-5-chlorobenzimidazole

21 grams of 2-methylmercapto-4-aza-5-chlorobenzimidazole were heated 4 hours at 170-180° C. with 110 grams of benzylamine. Upon cooling the desired compound crystallized. The cold reaction mixture was stirred with methanol, the crystals were sucked off and subsequently washed with methanol. The product was recrystallized from dimethyl formamide. Yield 16 grams; M.P. 280-285° C.

13

EXAMPLE 13

2-Anilino-4-aza-5-chlorobenzimidazole

30 grams of 2-methylmercapto-4-aza-5-chlorobenzimidazole were heated at 170–180° C. for 5 hours with 160 ml. aniline. The desired compound crystallized out in part during the reaction. The cold reaction mixture was stirred with ethyl alcohol, the crystals were sucked off and subsequently washed with alcohol. The product was recrystallized from dimethyl formamide. Yield 20 grams; M.P. >300° C.

EXAMPLE 14

2-Hydroxyethylamino-4-aza-5-chlorobenzimidazole

30 grams of 2-methylmercapto-4-aza-5-chlorobenzimidazole were heated for 7 hours at 170–180° C. with 160 grams of ethanalamine. Then the excess ethanalamine was distilled off in a vacuum. The residue was stirred with ethyl alcohol, whereupon it crystallized. The crystals were sucked off and subsequently washed with alcohol. They were recrystallized from n-propanol. Yield 13 grams; M.P. 236–238° C.

EXAMPLE 15

1-Benzyl-2-hydroxy-4-aza-5-chlorobenzimidazole

28 grams of 2-amino-3-benzyl-amino-6-chloropyridine in 200 ml. of dioxane were mixed with 10 ml. of pyridine and with stirring with 12.5 ml. of ethyl chloroformate. The product which crystallized out was filtered off with suction. Yield 20 grams; M.P. 200° C.

The thus obtained 2-amino-3-(N-benzyl) carbethoxyamino-6-chloropyridine was heated for one hour at 270–280° C. The melt was dissolved in ethanol and brought to crystallization. Yield 8 grams; M.P. 188–190° C.

EXAMPLE 16

2-Hydroxy-4-aza-5-fluoro-benzimidazole

To a solution of 10 grams 2-hydroxy-4-aza-5-amino-benzimidazole in 30 ml. 40% aqueous hydrofluoride acid

14

a solution of 10 grams sodiumnitrite in 20 ml. water is added in portions at 0–5° C. with stirring. The reaction product crystallizes from the reaction mixture within one hour. It is analytically pure. Yield 7 grams; M.P. 300° C.

5 What is claimed is:

1. A 4-aza-benzimidazole of the formula

10 where R_1 is chlorine or bromine, R_2 is hydrogen, straight chain 1–6 carbon alkyl, R_3 is hydrogen, straight chain alkyl of 1–6 carbon atoms, benzyl or $-\text{CH}_2\text{COOH}$, Y is hydroxy, mercapto, beta-hydroxyethyl-amino, benzyl-amino, straight chain alkyl mercapto of 1–6 carbon atoms, phenylamino, straight chain alkyl with 1–6 carbon atoms, benzyl or $-\text{SCH}_2\text{COOH}$ and pharmacologically acceptable salts thereof.

15 2. A compound according to claim 1 wherein R_1 is chlorine and R_2 is hydrogen.

20 3. A compound according to claim 2 wherein Y is hydroxy, mercapto, straight chain alkyl of 1 to 6 carbon atoms.

25 4. A compound according to claim 3 wherein R_3 is hydrogen.

30 5. A compound according to claim 3 wherein R_3 is straight chain alkyl of 1 to 6 carbon atoms.

35 6. A compound according to claim 5 wherein R_3 is straight chain alkyl of 1 to 3 carbon atoms.

7. A compound according to claim 3 wherein R_3 is $-\text{CH}_2\text{COOH}$.

40 8. A compound according to claim 1 where R_1 is chlorine, R_2 is hydrogen or straight chain alkyl of 1–6 carbon atoms, R is hydrogen, straight chain alkyl of 1–6 carbon atoms or $-\text{CH}_2\text{COOH}$, Y is hydroxy, mercapto, straight chain alkyl with 1–6 carbon atoms or benzyl.

45 9. A compound according to claim 8 wherein any alkyl present has 1 to 2 carbon atoms.

10. A compound according to claim 9 wherein any alkyl is methyl.

45 11. A compound according to claim 1 which is 2-mercapto-4-aza-5-chlorobenzimidazole.

12. A compound according to claim 1 which is 2-methyl-4-aza-5-chlorobenzimidazole.

13. A compound according to claim 1 which is 2-benzyl-4-aza-5-chlorobenzimidazole.

50 14. A compound according to claim 1 which is 2-hydroxy-4-aza-5-bromo-7-methyl benzimidazole.

15. A compound according to claim 1 which is 2-methyl-4-aza-5-chlorobenzimidazolyl-(1)-acetic acid.

55 16. A compound according to claim 1 which is 1-methyl-2-hydroxy-4-aza-5-chlorobenzimidazole.

UNITED STATES PATENT OFFICE
CERTIFICATE OF CORRECTION

Patent No. 3,819,640

Dated June 25, 1974

Inventor(s) Walter vonBebenborg

It is certified that error appears in the above-identified patent
and that said Letters Patent are hereby corrected as shown below:

Column 1, insert -- Claims priority of Austrian Application
No. A/7488/71 filed August 26, 1971 --.

Signed and sealed this 1st day of October 1974.
